Des. 210,490
Patented Mar. 12, 1968

210,490

METER OR SIMILAR DEVICE

Charles M. Dole, Jr., Mount Kisco, N.Y., assignor to
Corning Glass Works, Corning, N.Y., a corpora-
tion of New York

Filed Feb. 23, 1967, Ser. No. 5,924

Term of patent 14 years

(Cl. D52—6)

Fig. 1

Fig. 7

Fig. 2

Fig. 3

Fig. 4

Fig. 5

Fig. 6

FIG. 1 is a perspective view of a meter or similar device embodying my design.

FIG. 2 is a side elevational view thereof.

FIG. 3 is a front elevational view thereof.

FIG. 4 is a side elevational view thereof.

FIG. 5 is a back elevational view thereof.

FIG. 6 is a sectional view taken on line 6—6 of FIG. 5.

FIG. 7 is a top view thereof.

Except for the legs, the bottom of the device is substantially flat and plain.

I claim:

The ornamental design for a meter or similar device, substantially as shown and described.
